UNITED STATES PATENT OFFICE

171,074

COFFEE MAKER

Antonio Balboni, Ferrara, Borgo Uccelli, Italy, assignor to Calecenter Trading Corp., Fresno, Calif., a corporation of California

Application February 10, 1953, Serial No. 23,545

Term of patent 14 years

(Cl. D44—26)

To all whom it may concern:

Be it known that I, Antonio Balboni, a citizen of Italy, residing at Ferrara, Borgo Uccelli, Italy, have invented a new, original, and ornamental Design for a Coffee Maker, of which the following is a specification, reference being had to the accompanying drawing, forming a part hereof.

Fig. 1 is a top plan view of a coffee maker showing my new design.

Fig. 2 is a front elevational view of the coffee maker.

Fig. 3 is a side elevational view of the coffee maker. The side of the coffee maker opposite to that illustrated in Fig. 3 is of the same ornamental appearance.

I claim:

The ornamental design for a coffee maker, as shown and described.

ANTONIO BALBONI.
